CLAIM

The ornamental design for a medal holder, as shown and described.

DESCRIPTION

FIG. 1 is a top, front and right side perspective view of a medal holder showing my new design;

FIG. 2 is a bottom and front side perspective view thereof;

FIG. 3 is a left plan view thereof;

FIG. 4 is a right plan view thereof;

FIG. 5 is a front plan view thereof;

FIG. 6 is a rear plan view thereof;

FIG. 7 is a top plan view thereof;

FIG. 8 is a bottom plan view thereof; and,

FIG. 9 is an exploded perspective view thereof.

The dashed broken lines depict portions of the medal holder that form no part of the claim.

1 Claim, 9 Drawing Sheets
